E. G. GARTIN

ROCK DRILLING MECHANISM

Filed Dec. 28, 1922

Fig. 1.

UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

ROCK-DRILLING MECHANISM.

Application filed December 28, 1922. Serial No. 609,399.

My invention relates to rock drilling mechanism, and more particularly to improved controlling mechanisms for rock drilling mechanisms of the pneumatically fed type.

An object of my invention is to provide an improved rock drilling mechanism. Another object of my invention is to provide an improved rock drilling mechanism of the pneumatically fed type having improved controlling means. A further object of my invention is to provide an improved rock drilling mechanism of the so-called stoper type having improved means for enabling a ready and absolute control of said mechanism. Other objects and advantages of my invention will hereinafter more fully appear.

In the accompanying drawings I have shown for purposes of illustration two forms which my invention may assume in practice.

In these drawings,—

Fig. 1 is a side elevation, with parts broken away, of one form which my invention may assume in practice.

Fig. 2 is an enlarged detail sectional view showing details of one form of my improved controlling mechanism.

Fig. 3 is a view similar to Fig. 2 showing a modified form of construction.

In the accompanying drawings I have for purposes of illustration shown my invention used in connection with a drilling mechanism of the so-called stoper type, which mechanism is generally designated 1. This mechanism comprises a motor 2 adapted to percussively actuate a hollow drill steel 4. At the rear end of the motor is an intermediate head block 5 to which there is connected a motor and feed controlling means in the form of a valve mechanism whose controlling lever 6 is seen to the left of Fig. 1. This mechanism controls the supply of motive fluid to the drill motor 2 and controls the fluid supply for a feeding mechanism generally designated 7. The feeding mechanism comprises a feed cylinder 8, herein connected to the intermediate head and having a bore 9 in which a piston 10 is arranged. The piston 10 has a piston rod 11 which terminates at its end in an abutment engaging point 12. During operation the point 12 is placed in engagement with a fixed abutment and upon admission of air to the feed cylinder bore 9 at a point above

the piston 10, the feed cylinder 8 and the drilling motor 2 are simultaneously fed forward.

For the purpose of providing a more adequate and instantaneous control of the operation of the feeding mechanism than can be accomplished by the handle 6, I have arranged upon a laterally projecting handle 14 (which handle is in general outline similar to those customarily used for supporting or rotating stoping drills during operation and which includes a manual grasping portion 15 projecting at right angles to the drilling mechanism and a second portion 16 at right angles to the main portion 15) suitable controlling mechanism which I shall now describe. In the form of my invention shown in Figs. 1 and 2, the handle 14 is made hollow, as indicated at 17, to form a chamber in which lubricant may be stored, and at its outer end is provided with a transverse slot 18 in which a lever 19 of the general shape of a bell crank lever and having angularly related manual grasping portions 20 and 21 is pivoted. This lever is suitably connected by a pin and slot connection 22 with a rod 23 which extends through the chamber 17 and into a chamber 24 formed in part in the inner end of the handle 14 and in part in a boss 25 on the intermediate head 5. Within the chamber the rod is provided with a collar 26 with which a spring 26' cooperates to move the rod toward the right in Fig. 2. At its extreme left hand end in Fig. 2, that is, its end nearest the axial line of the drilling mechanism, the rod is formed with a valve portion 27 which cooperates with a port 28 leading from and controlled by the valve mechanism 6, and this valve portion 27 controls the passage of fluid from the port 28 to a passage 29 leading to the upper end of the bore of the feed cylinder 8. A valve seat 30 with which the end of the rod 23 may cooperate permits the complete interruption of fluid supply from the port 28 to the port 29.

The mode of operation of this form of my invention will be readily apparent. The drill runner can, by grasping either the portion 15 or the portion 16 of the handle and simultaneously grasping the arms 20 or 21 of the lever, cause the valve portion 27 to partially or wholly close communication between the ports 28 and 29 and so may control the rate of feed. It will be evident that

at whichever of the two places the handle may be grasped, it will be readily possible to control the operation of the feed.

In the form of my invention shown in Fig. 3, I have illustrated a modified form of controlling mechanism. The handle 14' is provided with similar portions 15' and 16' and with a transverse slot 18'. A branched lever mechanism 32, which has angularly disposed grasping portions 33 and 34, is pivoted as at 35 with its third arm 36 projecting into the slot 18'. The last mentioned arm is connected by a pin and slot connection 37 with a rod 38 extending through a portion of the handle 14'. The rod 38 at its left hand end, that is, the end nearest the axis of the controlling mechanism, is provided with a plurality of grooves 39 and 40 separated by a head or spool 41 and adjacent its extreme inner end is a second cylindrical portion 42 similar in diameter to the portion 41. A button 43 is formed at the end of the portion 42 and a spring 44 housed in the chamber 45 in the boss 25 together with an opposing spring 46 in an opposite chamber 47, normally maintains the rod 38 in the position shown in Fig. 3. A passage 28' leads from the valve member 6 and a passage 29' leads to the bore of the feed cylinder, as in the preceding construction, while a vent 48 to atmosphere is arranged on the opposite side of the port 29' from the passage 28'.

The mode of operation of this form of my invention will be readily apparent. Assume that the portion 16' of the handle and the arm 34 of the lever 32 are tightly grasped. This will cause a movement to the left of the rod 38 in a manner to interrupt the supply of fluid from the ports 28' and 29', a sufficiently great angular movement of the lever arm 34 toward the handle portion 16' being sufficient to interrupt communication entirely between the passages 28' and 29' and so to interrupt the feed promptly. On the other hand, the simultaneous tight grasping of the portion of the handle 15' and the lever arm 33 will move the rod 38 to the right and will not only interrupt the communication between the ports 28' and 29' by the overrunning of the latter by the spool 41, but will furthermore interconnect the port 29' with the vent 48 to the atmosphere so that the force of the feed will be practically instantly discontinued. It will thus be seen that, no matter which handle 33 or 34 is moved, the feed will be reduced by the closure of communication between the passages 28' and 29' and it will be further noted that if the handle 33 is grasped, the vent 48 will be opened and so the reduction in feed pressure will be even more prompt.

While I have in this application specifically described two forms which my inven-

tion may assume in practice, it will be understood that these forms of the same are shown for purposes of illustration and that the invention may be modified and embodied in other forms without departing from its spirit or the scope of the appended claims.

What I claim as new and desire to secure by Letters Patent is:

1. In a drilling mechanism, the combination with drill feeding means and a handle projecting from the drill and having angularly disposed grasping portions, of feed controlling means comprising a controlling element, and operating means for said element including an operating member having angularly related operating portions disposed in juxtaposition with said grasping portions.

2. In a drilling mechanism, the combination with a fluid actuated feeding means and a drill supporting handle projecting laterally at one side of the drill and having angularly disposed grasping portions, of means for controlling said feeding means including angularly related controlling elements disposed in juxtaposition with said grasping portions.

3. In a drilling mechanism, the combination with a pressure fluid actuated feeding means and a drill supporting handle projecting laterally at one side of the drill and having angularly disposed grasping portions, of means for controlling said feeding means including a valve, and operating means for said valve including angularly related controlling elements cooperating therewith disposed in juxtaposition with said grasping portions.

4. In a drilling mechanism, the combination with a fluid actuated feeding means and a supporting handle projecting laterally at one side of the drill and having angularly disposed grasping portions, means for controlling said feeding means including a valve movably mounted within one of said grasping portions, and means for operating said valve including angularly related controlling elements cooperating therewith disposed in juxtaposition with said grasping portions.

5. In a drilling mechanism, the combination with a pressure fluid actuated feeding means, and a drill supporting handle extending laterally at one side of the drill and having angularly disposed grasping portions at its outer extremity, of feed controlling means including a valve for enabling the operator to control the pressure in said feeding means in accordance with the requirements of the work, and operating means for said valve including an operating element having angularly related grasping portions disposed in juxtaposition with the grasping portions of said handle.

6. In a drilling mechanism, the combination with a pressure fluid actuated feeding means, and a drill supporting handle extending laterally at one side of the drill and having angularly disposed grasping portions at its outer extremity, of feed controlling means including a valve for enabling the operator to control the pressure in said feeding means in accordance with the requirements of the work, and operating means for said valve including a pivoted element having angularly related manually grasping lever portions disposed in juxtaposition with the grasping portions of said handle.
- 10 5 15 20 25
7. In a drilling mechanism, the combination with a fluid actuated feeding means, and a drill supporting handle comprising manually graspable portions disposed at an angle to each other, of controlling means for said feeding means including a valve, and means for controlling the position of said valve including lever mechanism having angularly related arms operable by a hand

resting upon either grasping portion of said handle.

25

8. In a drilling mechanism, the combination with fluid actuated feeding means and a drill supporting handle having angularly disposed manually graspable portions, of controlling means for said feeding means including a valve movable in opposite directions and operable when so moved respectively to interrupt fluid supply to said feeding means and both to interrupt fluid supply to said feeding means and open a vent therefrom, and means controlling said valve including lever mechanism having angularly related arms disposed adjacent said angularly disposed grasping portions, said arms being so disposed relative to said portions that when moved into parallelism thereto they effect movement of said valve in opposite direction.

In testimony whereof I affix my signature.

ELMER G. GARTIN.
